CLAIM

The ornamental design for a plaque, as described and shown in the drawings.

DESCRIPTION

FIG. 1 is a top perspective view of a plaque showing my new design, the document shown in broken lines for illustrative purposes only, the bottom being plane and unornamented;

FIG. 2 is a side elevational view thereof, the opposite side being identical; and,

FIG. 3 is an enlarged cross-sectional view thereof, taken in the direction of the arrows along line 3—3 of FIG. 1.

1 Claim, 1 Drawing Sheet

FIG. 3.
